UNITED STATES PATENT OFFICE.

CHARLES H. PALMER AND JOHN W. DENMEAD, OF AKRON, OHIO, ASSIGNEES TO THE
DIAMOND MATCH COMPANY, OF CHICAGO, ILLINOIS, A CORPORATION OF ILLINOIS.

MATCH.

985,833.

Specification of Letters Patent.

Patented Mar. 7, 1911.

Application filed July 21, 1909. Serial No. 508,709.

To all whom it may concern:

Be it known that we, CHARLES H. PALMER and JOHN W. DENMEAD, citizens of the United States, and residents of Akron, in the county of Summit and State of Ohio, have invented certain new and useful Improvements in Matches, of which the following is a specification.

This invention relates to the manufacture of matches, and has for its object to provide a cheap and efficient match having a composite splint of wood and paper arranged in superposed layers, whereby the wood reinforces the paper and serves to prevent the bending thereof during the act of striking the match, and whereby the paper obviates all liability of the separation and falling of the parts in the event of the breaking of the wood, and, being of soft stock, absorbs sufficient paraffin, or the like, to insure the ready ignition of the splint when the head thereof is ignited.

Other advantages resulting from our invention will be hereinafter pointed out.

In the drawings—Figure 1 is a perspective view of a match (enlarged) embodying our invention. Fig. 2 is a similar view illustrating the improvement as applied to a match card. Fig. 3 is a view of an ordinary match book containing sections of the said card.

Referring to Fig. 1 of the drawings, *a* represents two strips or layers of paper, and *b* a thin strip or layer of veneer interposed between the same, the whole being intimately cemented together to constitute a homogeneous stem or splint. The edges of the interposed strip of veneer are exposed throughout the length of the splint so that when the latter is dipped at one end into the usual liquid paraffin, the veneer, as well as the paper, is treated therewith, as at *c*, and also when the usual head of ignitable composition, *d*, is applied to such end, the composition comes into direct contact with the wood, as well as with the paper. Thus, it will be seen that if the head of the match be ignited, the flame produced will be communicated directly to the inner and lateral layers of material and thereby facilitate and insure the ignition of the splint. It will also be seen that by our invention a cheap and common grade of wood may be utilized for the middle layer, in that the outer layers of paper not only cover and protect the

same laterally, but also obviate the otherwise liability of the separation and falling of the parts in the event of the breaking of the wood while striking the match. Moreover, soft and absorbent paper for the outer layers may be used, in that the wood reinforces the same and imparts the requisite rigidity thereto.

It is to be noted that paper matches are made of cheap, soft stock in order to permit the absorption thereby of sufficient paraffin, or the like, to insure combustion, but such material, lacking rigidity, bends easily when the match is being struck. Also that veneer matches are necessarily made of selected straight-grained stock in order that they shall possess the requisite strength and rigidity. In the production of our improved matches, however, we are enabled to secure and combine the absorbent and rigid characteristics of paper and wood without recourse to expensive stock.

In the practical manufacture of these matches we produce a thin sheet or layer of veneer in the usual manner and cement to and throughout its upper and lower surfaces the layers of paper. We then sever from the composite sheet splints of proper length and breadth and treat them with paraffin and ignitable composition in any known or improved manner.

In Fig. 2 we have shown our invention as embodied in a match card, the splints (*a*) being only partially severed from the sheet of composite material so as to leave a marginal connecting portion *a'*. The free ends of the splints are staggered or laterally separated, as indicated, and then dipped in the paraffin and ignitable composition.

In Fig. 3 we have illustrated a construction in which the match card is divided into sections and contained within a suitable cover *e*, similarly to the well-known match book; the parts being united by a staple, as *f*, driven through the folded end of the cover and the interposed margins of the confined sections. The paper layers of the card material obviate any liability of the splitting of the marginal portions of the cards when the staple is driven therethrough.

We claim—

1. As a new article of manufacture, a match comprising in its construction flat strips or layers of paper and a thin strip or layer of wood interposed between the

same, the whole being intimately cemented together to constitute a homogeneous stem or splint.

2. As a new article of manufacture, a match comprising in its construction flat strips or layers of paper and a thin strip or layer of wood interposed between the same, the whole being intimately cemented together to constitute a homogeneous stem or splint, and the edges of the wood being exposed.

3. As a new article of manufacture, a match card comprising a thin sheet or layer of wood and layers of paper intimately cemented to and throughout the upper and

lower surfaces of the wood, the whole being partially severed to provide a series of composite match splints having a marginal connecting portion, and the free ends of the splints being saturated with paraffin and 20 tipped with ignitable composition.

Signed at Barberton in the county of Summit and State of Ohio this 16th day of July, 1909.

CHARLES H. PALMER.
JOHN W. DENMEAD.
